UNITED STATES PATENT OFFICE.

HENRY ALBERT, OF CRESCENT CITY, CALIFORNIA.

ELEVATOR.

SPECIFICATION forming part of Letters Patent No. 333,713, dated January 5, 1886.

Application filed October 27, 1885. Serial No. 181,106. (No model.)

To all whom it may concern:

Be it known that I, HENRY ALBERT, of Crescent City, county of Del Norte, and State of California, have invented an Improvement 5 in Elevators; and I hereby declare the following to be a full, clear, and exact description thereof.

My invention relates to the class of elevators and to those appliances or connections by 10 which the cage is caught and held in case the rope breaks.

My invention consists in peculiar racks in the elevator-shaft, anti-friction guide-wheels on the cage, sliding bolts in said wheels, and 15 mechanism dependent upon and operated by the central spring-actuated spindle, to which the lifting-strain is applied for projecting and retracting the bolts to cause them to engage with or to be disengaged from the racks.

20 It consists, further, in various details of construction relating to the several parts, and in a peculiar buffer on the bottom of the cage for the purpose of breaking its fall, if for any cause it should reach the base of the shaft.

25 The object of my invention is to provide a simple and effective safety-elevator.

Referring to the accompanying drawings, Figure 1 is a perspective view of my elevator. Fig. 2 is a perspective detail of the safety 30 mechanism. Fig. 3 is a horizontal section through the rack and the wheel E, showing the interior mechanism, and also the bolts G, as adjustable in the heads F. Fig. 4 is a vertical section of the wheel E, showing the bolts 35 rigid in the heads. Fig. 5 is a detail of the buffers R.

A is the elevator shaft or well, in the sides of which are formed grooved or slotted ways a, provided with transverse cross-pins a', said 40 ways and pins forming vertical racks.

B is the cage, having in its top a vertically-sliding spindle, b, which is influenced by an elliptical spring, b'. To the upper end of the spindle is secured the suspending cord or rope 45 C. On the top of the cage are bearings or standards D, in which are mounted the axles e of the anti-friction rollers or wheels E, which are adapted to travel against the wall of the elevator-shaft between its racks. These roll- 50 ers or wheels are made hollow, and their journals or axles are also made hollow or tubular,

Figs. 3 and 4. Within the wheels are the disks or heads F, which carry the bolts G, which project outwardly through the sides of the wheels or rollers, and when so projected 55 are adapted to engage the cross-pins of the racks.

Secured to the heads F of the rollers are rods H, which extend outwardly through the hollow journals or axles e and have their 60 outer ends connected with the pivoted levers I, Fig. 2. Mounted in the top center of the standards are blocks or studs J, which are adapted to slide in and out. The inner ends of the studs are connected by links or toggles 65 K with the lower end of the spring-actuated spindle b, by which the cage is suspended, while their outer ends are connected with the pivoted levers I. Springs L bear against the blocks or studs, and serve to force them in. 70

The operation, as far as explained, is as follows: When the lifting or supporting strain is applied to the spindle b, it draws said spindle up against its spring b', thus forcing outwardly the studs or blocks J, and through the 75 pivoted levers I causing the rods H, which pass through the hollow journals e of the wheels, to force inwardly the heads F within said wheels, thus retracting the bolts G, so that they are out of the way within the wheels. 80 As long as this lifting-strain remains the bolts lie within the wheels, but as soon as the strain is relieved—as by the breaking of the supporting cable or rope—the spring of the spindle b forces said spindle down, thus drawing in the blocks or studs J, which movement is assisted by their own springs L. The rods H are thus drawn outwardly, which draw on the heads F within the wheels, and project the bolts G, some of which, in the revolution of the 85 anti-friction wheels against the walls of the shaft, will engage with the cross-pins a' of the racks, and thus hold the cage. These bolts not only act in the capacity of stops, but also as chokes or brakes, for it will be seen that 90 as the cage descends too rapidly several of the projected bolts in the sides of the rotating rollers will bind against the surfaces of both walls of the grooved rackways, and thus check or brake the cage until the engagement of the 95 bolts with the cross-pins is effected. 100

In order to prevent any of the bolts from

striking squarely against the edge of the inner wall of the grooved way, and thus prevent the full operation of the mechanism, I bevel down this edge of the inner wall, as shown at *m*, 5 and I also make the points of the bolts on a bevel, Fig. 3; but to entirely obviate any danger of this kind I may have the following mechanism:

By referring to Fig. 3 it will be seen that 10 the bolts *G* pass loosely through the heads *F*, and are themselves provided with heads *g*, which keep them in their seats, while still allowing them a certain movement of their own independent of the heads *F*. Springs *N* bear 15 on the heads *g* of the bolts. Now, if any one of the bolts should come in contact squarely with the edge of the grooved way, it could yield against its spring, and not prevent the proper movement of the remainder of the bolts; 20 but, ordinarily, it may be found practical for all purposes to secure the bolts rigidly to the heads.

On the bottom of the cage are two anti-friction rollers or wheels *O*, which simply serve as 25 guides for the cage. To the bottom of the cage are bolted the pieces *Q*, which are hollowed out or socketed to receive the stems *r* of the rubber buffers *R*, Figs. 1, 5. Within the sockets of pieces *Q* are springs *S*, against which 30 the ends of the stems of the buffers bear. This mechanism is to relieve the jar, or break the fall of the cage, should it by any chance reach the bottom.

In order to provide for an accurate lineal 35 movement of the rods *H*, it is necessary that the connection between their outer ends and the ends of the pivoted levers *I* should be a movable or adjustable one. This may be accomplished by means of the sliding and swiveling bearings *T*, in a groove in the levers *I*, and to which the rods *H* are connected, Fig. 2, or it may be done by simply slotting the levers over the rods, and confining the latter by two heads or collars, as shown in Fig. 3.

45 It is obvious that I might duplicate the safety appliance in the lower rollers and make the same suspending-spindle operate them.

Having thus described my invention, what I claim as new, and desire to secure by Letters 50 Patent, is—

1. In an elevator, the combination of racks in the shaft with anti-friction rollers or wheels on the cage traveling in the shaft, and sliding bolts in the rollers or wheels adapted to be 55 projected within the racks when the supporting-strain on the cage is relieved, and to be retracted when the strain is applied, substantially as described.

2. In an elevator, the combination of racks in the shaft with anti-friction rollers or wheels on the cage traveling in the shaft, sliding bolts in the rollers or wheels, a yielding spring-spindle on the cage, to which the lifting or supporting strain is applied, and mechanism 65 connecting the spindle with the bolts, whereby when the strain on said spindle is relieved the

bolts are projected to engage the racks, and when the strain is again applied to the spindle the bolts are retracted, substantially as described.

3. In an elevator, the shaft *A*, having the grooved or slotted ways *a* in its sides, with cross-pins *a'*, forming racks, in combination with the cage *B*, having the anti-friction rollers or wheels *E* in the sides of its top traveling against the walls of the shaft between the racks, and the sliding bolts *G* in the rollers or wheels adapted to be projected through their sides to engage with the racks when the supporting-strain on the cage is relieved, and to be retracted into the rollers or wheels when the strain is applied, substantially as described. 70

4. In an elevator, the shaft *A*, having the grooved or slotted ways *a* in its sides, with cross-pins *a'*, forming racks, in combination 75 with the cage *B*, having the anti-friction rollers or wheels *E* in the sides of its top traveling against the walls of the shaft between the racks, the sliding bolts *G* in said rollers or wheels, the sliding spring-actuated spindle *b* 80 in the top of the cage, to which the supporting or lifting strain is applied, and connecting mechanism between the spindle and the bolts, whereby the latter are projected and retracted to engage with or to be disengaged from the 85 racks according as the strain is relieved or applied, substantially as described. 90

5. In an elevator, the vertical racks in the elevator-shaft, consisting of the grooved ways *a* and cross-pins *a'*, the innermost edge of the 95 ways being beveled, in combination with the rollers or wheels *E* of the cage, having sliding bolts *G*, adapted to be projected and retracted, as described, said bolts having beveled points, substantially as and for the purpose herein 100 described.

6. In an elevator, the hollow anti-friction rollers or wheels *E* on the reciprocating cage having hollow journals or axles *e*, by which 105 they are mounted, in combination with the sliding heads *F* in the wheels, the rack-engaging bolts *G*, attached thereto and projecting through the sides of the rollers or wheels, the rods *H*, passing through the hollow journals *e* and connected with the heads *F*, and a mechanism for reciprocating said rods, substantially 110 as herein described. 115

7. In an elevator, the hollow anti-friction rollers or wheels *E* on the reciprocating cage having hollow journals or axles *e*, by which 120 they are mounted, in combination with the sliding heads *F* in the wheels, the rack-engaging bolts *G*, projecting through the sides of the wheels and headed loosely in the heads, the adjusting-springs *N*, pressing on the heads of the bolts, the rods *H*, passing through the hollow journals *e* and connected with the heads *F*, and a mechanism for reciprocating said rods, substantially 125 as herein described.

8. The hollow anti-friction rollers *E* of the 130 elevator-cage, in combination with the heads *F* within the rollers, the sliding bolts *G*, pass-

ing through the sides of the rollers and loosely headed on the heads F, and the springs N, pressing on the heads of the bolts, substantially as herein described.

5 9. In an elevator, the cage B and the sliding spring-actuated spindle b, by which it is suspended, in combination with the hollow anti-friction rollers or wheels E, having hollow journals or axles e, by which they are 10 mounted in the cage, the sliding heads F within the rollers, the bolts G, carried thereby and adapted, when projected, to engage racks in the elevator-shaft, the rods H, passing through the hollow journals e and connected with the 15 heads, the pivoted levers I, connected with said rods, the sliding blocks or studs J, connected with the levers, the links or toggles K, connecting the spindle and the sliding blocks, and the springs L, bearing against said blocks, 20 substantially as herein described.

10 10. In an elevator, the shaft A, having the grooved ways a, with cross-pins a', forming racks, and the cage B, having a spring-actuated spindle, b, by which it is suspended, in 25 combination with the hollow anti-friction wheels or rollers E, having hollow journals or axles e, by which they are mounted on the cage, the sliding heads F within the rollers, the adjustable bolts G, carried by the heads 30 and adapted to engage the racks, the rods H,

passing through the hollow journals e and connected with the heads F, the pivoted levers I, connected with the rods, the sliding blocks or studs J, connected with the levers, the toggles or links K, connecting the spindle with 35 the sliding blocks, and the springs L, bearing against said blocks, substantially as herein described.

11. In an elevator, the hollow wheels or rollers E on the cage having the hollow axles 40 or journals e, and the heads F, with the rack-engaging bolts G, operating as described, in combination with the rods H, passing through the hollow axles, the pivoted levers I, operated as described, and a sliding or movable pivot-connection between the levers and rods, by which the latter are moved in a straight line, substantially as described.

12. The bolt-operating rods H and the pivoted levers I, in combination with the bearings T, pivoted and sliding in grooves in the end of the levers and connected with the rods H, substantially as described.

In witness whereof I have hereunto set my hand.

HENRY ALBERT.
